UNITED STATES PATENT OFFICE.

ALBERT E. WAGGONER, OF CHICAGO, ILLINOIS, ASSIGNOR OF ONE-HALF TO GEO. W. DIENER MFG. CO., OF CHICAGO, ILLINOIS, A CORPORATION OF ILLINOIS.

FIRE EXTINGUISHER.

Application filed May 23, 1919. Serial No. 299,245.

To all whom it may concern:

Be it known that I, ALBERT E. WAGGONER, a citizen of the United States, and a resident of Chicago, in the county of Cook and State of Illinois, have invented certain new and useful Improvements in Fire Extinguishers, of which the following is a full, clear, and exact description.

The invention relates to fire extinguishers and more particularly to that type in which there is provision for separately retaining a chemical and water in readiness to be mixed when occasion arises for the use of the extinguisher.

One object of the invention is to provide an improved extinguisher which can be used without causing the chemical and water to be mixed when the extinguisher is inverted in a fire drill to familiarize the employees with the use of the extinguisher.

Another object of the invention is to provide an improved construction which causes the chemical to be thoroughly mixed with the water before it escapes.

Another object of the invention is to provide improved means for retaining the fragments of a broken bottle which contain the acid or chemical so that it will not interfere with the mixture of the chemical and water.

Another object of the invention is to provide improved means for indicating whether the bottle-breaker has been operated, so that an inspector can readily discern when the extinguisher is inoperative.

The invention consists in the several novel features hereinafter set forth and more particularly defined by claims at the conclusion hereof.

In the drawings: Fig. 1 is a side elevation of a fire extinguisher embodying the invention. Fig. 2 is a section. Fig. 3 is a similar view showing the extinguisher inverted and the chemical-bottle broken. Fig. 4 is a detail of the receptacle or cup for the fragments of the broken bottle. Fig. 5 is a detail of the bottle-holder or receptacle. Fig. 6 is a section taken on line 6—6 of Fig. 2.

The invention is exemplified in a fire extinguisher comprising a tank 8 provided with a discharge nipple 9, a hose 10 connected to said nipple, a screw-threaded collar 11 having a flange 12 engaging the inner face of the top of the tank 8 and a cover 13 which is screw-threaded to the collar 11 and

provided with a ring 14 for turning the cover on and off the collar to secure the cover and collar in place and form a tight enclosure for the top of the tank. A gasket 15 is interposed between the collar and the top. A screen 16 is provided in the tank adjacent the discharge opening leading to nipple 9. All of the parts thus far described may be of usual construction.

A bottle-holder 17 is provided with a flange 18 which is supported by lugs 19 on the collar 11 which are disposed so that the flange 18 will be held between the gasket 15 and said lugs to firmly secure the holder 17 normally suspended from the top of the tank and in place when the extinguisher is inverted. A bottle 20 rests upon the imperforate bottom 17' of the holder 17. A normally inverted cup 21 fits over the top and upper portion of the bottle and is provided with lugs 22 which are adapted to strike the usual ledge on the bottle and break the latter when the cup is subjected to a blow by a breaker comprising a hammer 23 on a stem 24 which is slidably held in the cover and is provided with a flanged top member 25. A blow upon the member 25 will be transmitted through the stem 24 to the hammer 23 and thence to the cup 21 so that the lugs 22 will break the bottle. The upper portion of the inverted cup is convergent, as at 26, and provided with lugs 27 which position the upper portion of the cup centrally in the bottle-holder 17. Small openings 30 are formed adjacent the upper portion of the inverted cup 21 for the escape of the acid or chemical released when the bottle is broken and the extinguisher is inverted. Holes 31 are formed at one side of, and adjacent the upper end of, the holder 17 so that the chemical can escape therefrom into the chamber of tank 8. The openings 31 are disposed in that side of holder 17 which is remote from the outlet nipple 9, so that the chemical cannot pass directly from the holder outlet. In practice, it has been found to sometimes cause injury to the operator if the chemical finds direct passage to the discharge without being mixed with water. A spring 29 is interposed between the head 25 and the cover 13 to hold the breaker normally raised. A lug 31' is formed on the holder 17 which is adapted to fit in a notch in one of the lugs

19 to position the holder so that the holes 31 will always be correctly disposed with respect to the discharge nipple.

A glass tube 34 is interposed between the 5 top of the cover 13 and the flange of the top-member 25 of the breaker and this serves as a seal which must be broken before the breaker can be operated to break the bottle and release the chemical.

10 In operation, the parts will be normally held in position shown in Fig. 2. At such time, the acid in the bottle 20 will be kept so that it will not evaporate or deteriorate because the cork can form an effective closure.

15 It is sometimes desirable to practice the operation of the fire extinguishers in fire-drills precisely the same as is done in actual use; including the inversion of the extinguisher as a whole, and this can be done without releasing any of the chemical in the bottle 20.

20 When, however, the extinguisher is to be used for a fire, the operator will invert the extinguisher and impart a blow to the member 25 of the breaker which will break the seal 34 and cause the lugs 22 to break the

25 bottle and release the acid. The acid or chemical normally held in bottle 20 will pass gradually through the small openings 30 in cup 21 and escape into the holder 17 and the

30 tank 8, where it will mix with the water and form the desired extinguishing solution. The cup 21, when the extinguisher is inverted, and the cup 17, when the extinguisher is in normal position, will retain the frag-

35 ments of glass and prevent them from passing out into the chamber in the tank. By locating the openings 31 in cups 17, remote from the strainer 16, the acid must necessarily mix with the water in the tank 8 before

40 it can reach the discharge.

A characteristic of the device is that when the tank has been inverted for a short time, and before all of the chemical has passed out

of the bottle-holder, and it is desired to return the tank to normal position to discontinue the delivery of the chemical to the water in the tank, the holder with its imperforate bottom portion will retain the chemical in the holder until the tank is again inverted.

45 The invention is not to be understood as restricted to the details set forth, since these may be modified within the scope of the appended claims, without departing from the spirit and scope of the invention.

50 Having thus described the invention, what I claim as new and desire to secure by Letters Patent, is:

55 1. In a fire extinguisher, the combination with a tank provided with discharge means, 60 of a holder for a bottle containing a chemical and having an imperforate bottom portion and openings near its upper end, an inverted cup held in the holder and adapted to contain the fragments of a broken bottle 65 and to restrict the outflow of chemical when the tank is inverted, and means to operate the cup to break a bottle.

2. In a fire extinguisher, the combination with a tank provided with discharge means, 70 of a holder for a bottle containing a chemical, an inverted cup movably held in the holder adapted to contain fragments of the broken bottle and having lugs thereon for striking the bottle, and a breaker adapted to 75 operate the cup to break the bottle.

3. In a fire extinguisher, the combination with a tank provided with discharge means, 80 of a holder for a bottle containing a chemical, an inverted cup movably held in the holder adapted to contain fragments of the broken bottle and provided with means for striking the bottle, and a breaker adapted to operate the inverted cup to break the bottle.

ALBERT E. WAGGONER.
